APPARATUS FOR HANDLING RECUMBENT PERSONS

John E. Lenahan, Cornwall on the Hudson, N. Y.

Application August 22, 1944, Serial No. 550,636

8 Claims. (Cl. 5—86)

1

This invention relates to apparatus for lifting, transferring and temporarily supporting persons in a reclining position and more particularly to such apparatus for so handling patients confined to hospital beds.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a perspective view of a portion of apparatus embodying the invention shown in use;

Fig. 2 is a fragmentary detail in perspective, of a strap fastening device;

Fig. 3 is an end elevation of a view similar to that disclosed in Fig. 1;

Fig. 4 is a fragmentary perspective showing a complete apparatus embodying the invention; and

Fig. 5 is a similar perspective on reduced scale showing said apparatus assembled to support a patient away from the bed.

The invention is directed to providing a new and useful device for facilitating the handling of persons in reclining positions, more especially patients confined to their beds, who require to be moved from the bed temporarily to permit changing thereof, treatment of the patient, and other purposes.

Objects of the invention are to permit the lifting and transfer of a reclining patient from his bed or similar support with the least possible disturbance of the patient and requiring the minimum of effort and physical strain on the part of the nurse or other attendant handling such patient. The invention also provides exceedingly simple, compact, rugged and relatively inexpensive equipment for so handling a recumbent patient. The mechanism is so designed that no mechanism need be attached to or otherwise mechanically connected to the bed and all overhanging or overhead cranes, slings or like elevating apparatus is eliminated, thereby mak-

2

ing for greater peace of mind on the part of the patient, as well as providing the maximum of safety and simplicity in operation and construction.

5 Broadly described, the invention provides for one or more concave scoops or patient-supports having projecting handles so that such scoops may, with a minimum of effort, discomfort and inconvenience, be inserted beneath the body of the recumbent patient while he is lying in the bed. The insertion of such supporting scoop is performed in a wholly natural and simple manner requiring very little effort on the part of the nurse or operator.

10 The other major unit comprising the apparatus of the invention is a portable stand provided with means for receiving and interlocking with the projecting handles of the above-mentioned supporting scoops. Said second unit also comprises means for thereafter elevating the scoop or scoops so as to raise the patient gently from the bed, whereby he may be moved away therefrom in a comfortable, safe and firmly supported position involving the minimum amount of lifting and with substantially no twisting, turning or change from his original position. The patient so supported may thereupon be moved to any desired place to permit access to the unoccupied bed or for transportation elsewhere, as may be desired. When the bed is again ready, the apparatus may be rolled back and the patient lowered thereupon and the scoop detached from the second unit and withdrawn from beneath the patient, all in a similar convenient and effortless manner.

15 It will be understood that the foregoing general description and the following detailed description as well are exemplary and illustrative of the invention but are not restrictive thereof.

20 Referring now in detail to the present preferred embodiment of the invention, illustrated by way of example in the accompanying drawings, a recumbent patient P is shown lying on his back on top of the mattress 10 of a simple hospital bed. Said bed comprises the head frame 11, the foot frame 12 and the inter-connecting spring frame 13. The head and foot frames are preferably mounted on casters 14. It will be understood that the bed as shown and described constitutes no necessary part of the invention.

25 In its preferred form the invention provides a pair of relatively long and narrow concave scoop members 20 and 21. Said scoops and the parts attached to them are equivalent and interchangeable in construction, so that only one of the pair

will be described in detail. The scoop 20, as shown, may be made of light metal, plywood or other light, rigid, strong material and in shape is essentially a portion of the wall of a cylinder of long radius. It is preferably about three feet in length and about two feet in width—that is, of a length equal or slightly less than half the height of an average person and of width such as to have its edges extend well on either side of such person when placed centrally beneath him. A handle 22, preferably comprising a rigid rectangular bar, is rigidly fastened, as by welding, to the central part of the underside of the scoop 20, the upper edge of said handle being arcuately cut away at 23 (Fig. 3) to fit snugly against the underside of the scoop. Said handle projects horizontally from the scoop at right angles to the elements of the cylindrical surface thereof, as shown. The handle bar 22 extends a distance of some two feet outwardly from the near edge of the scoop and at its outer end is provided with a reduced grip portion 24. About midway between its ends a rectangular collar 25 is fixed to the handle bar to form a stop member, and a second rounded grip portion 26 is formed inside and adjacent to said stop member.

As will be clear from the drawings, the nurse or operator N takes the handlebar 22 by the two grips 24 and 26 and, because of its smooth concave shape, can very easily insert the scoop beneath the patient lying on top of the mattress 10. This operation, as illustrated in Figs. 1 and 3, is performed by using the scoop 21 beneath the head and torso of the patient while the second scoop 20 may then be slid beneath the hips and legs in a similar manner. Preferably the two scoops are spaced somewhat apart at the hips to leave a space therebetween for greater supporting comfort and for purposes of possible treatment of the patient away from the bed. As will be noted from Figs. 1 and 3, the head of the patient may conveniently be left lying on a pillow 15 under which the scoop 21 may be readily inserted. The shape and construction of the scoops are such that virtually no discomfort or disturbance is caused to the patient by the complete insertion thereof beneath him, while the length, weight and balance of the handle are such that an effective leverage is provided so that even a relatively small or weak operator can very easily introduce the scoops beneath the heaviest patient.

Means may be provided for more securely fastening the patient to the scoops after same have been inserted beneath him, although such means are not essential to the primary objects of the invention and may be considered as optional. Such means comprise holding straps 27 which are retained on the outer edge of either scoop by means of spaced-apart perforations 28 in the end of the strap, one of said perforations being engaged by a spring-pressed pin 29. Said pin is adapted to pass slideably through a conforming opening in a U-shaped holding bracket 30 on the side edge of the scoop 20 and into a receiving recess 31 in said side of the scoop. A leaf-spring 32 is attached to said pin 29 to urge same into strap-holding position. It will be obvious that the end of the strap may be set at any one of the several perforations 28 for purposes of adjustment. The opposite end of the strap 27, which normally hangs free from the bracket 30, is provided with a strap hook 35, which hook is adapted to be engaged in a receiving slot 36 on the opposite or far side of the scoop 20. Thus,

as will be clear from Figs. 1 and 4, the strap may be brought across the body of the patient and fastened to the far side of the scoop after the scoop has been wholly inserted. The strap may then be drawn up to any desired position of tightness and thus the patient more securely retained in and on the scoop or scoops. It will be understood that other means for temporarily fastening the patient onto the scoops may be provided without departing from the general purposes of the invention, the chief object being to provide fastening means which will not interfere with the introduction of the scoop beneath the patient as shown in Fig. 3, for example.

Referring now to the second unit of the invention, same comprises means for elevating and supporting the patient apart from the bed and for moving him while so supported to any desired place. A preferred form of such apparatus is shown in Figs. 4 and 5 and comprise a rectangular, fairly heavy platform 40, which is mounted on rollers, wheels or casters 41 for movement over the floor, only two of such casters being shown.

Upstanding from the upper surface of said platform are provided a pair of cylinders 42 and 43, which cylinders are adapted to house the vertically slideable plunger members 44 and 45, respectively, of two hydraulic jacks. Referring to the jack plunger 44 (the plunger 45 being of equivalent construction) same comprises a solid cylindrical body having its bottom end, preferably flat and being of a diameter to form a tight sliding fit within the cylinder 42. The upper end of said plunger 44 is preferably beveled downwardly and rearwardly at 47, leaving a short flat top surface 48. The top end of said plunger is diametrically slotted at 50 to provide a receiving recess for the projecting end of the handlebar 22. The bottom of said slot 50 is horizontal and conforms to the bottom surface of the rectangular bar 22. As will be obvious from the drawings, the slot 50 is adapted to receive the projecting end of the bar 22 when the plunger 44, by movement of the platform 40, is brought into line with said handlebar. The grip portion 24 of said handlebar is adapted to project beyond the slot 50 and when in such position the stop member 25 of the bar bears against the inner surface of the plunger 44.

In order to lock the bar within the slot 50 and hold same in position, the upper surface of said bar is notched at 51 to receive a pin 52 which is passed through holes 53 in the ears 54 which extend in prolongation of the slot 50 on the plunger 44. When the bar 22 is thus received within the slot and the pin slid home, the bar is securely locked to the plunger against sliding or rocking movement and projects horizontally therefrom by cantilever support. The pin 52 may be attached to ear 54 as by a chain 55. It will be obvious that similar means are provided for attaching the handlebar of scoop 21 to the corresponding slot at the top of the plunger 45.

Means are provided for raising and lowering the plungers 44 and 45, preferably in unison, by hydraulic jack action. Such means are somewhat diagrammatically shown in Fig. 4 and it will be understood that the invention is not limited to such hydraulic means for this purpose, as same may be accomplished by means of mechanical gearing or other suitable devices, operated either manually or through power attachments. As shown, hydraulic pumps 60 and 61 are provided for forcing oil or other fluid from

the reservoir into the bases of cylinders 42 and 43, respectively, through suitable conduits as indicated. Said pumps are preferably actuated by a projecting pedal 62 which functions in a known manner similar to such device on a dentist's chair, for example.

Preferably, although not necessarily, the invention provides means for varying the lateral distance between the two hydraulic plungers 44 and 45. As illustratively embodied, this means comprises a U-shaped leaf spring member 70 which bears at its lower ends against the bottoms of the cylinders 42 and 43. While the bottom of cylinder 43 is fixed to the top of platform 40, as by rivets 71, the bottom of cylinder 42 is laterally slideable on the platform for a limited distance. As shown, the bottom plate 73 of the cylinder 42 underlies horizontal flanges 74 and 75 which are fixed to the upper surface of the platform so as to permit such horizontal sliding motion of the cylinder 42. To effect such motion, a curved lever 80 is pivotally mounted at 81 on the upper surface of the platform near the far edge thereof and projects upwardly to lie between the two cylinders 42 and 43. Intermediate its ends, said lever is pivotally connected to the top of the U-shaped spring 70, and continues outwardly and upwardly therefrom to terminate in a T-shaped head 82 which forms a handle. When the operator merely pushes or pulls horizontally on such handle, the platform will be moved correspondingly over the floor. However, by pressing down on such handle the spring 70 is expanded and thereby acts to force the cylinder 42 laterally away from the cylinder 43 and in this manner a horizontal spreading action between the two cylinders may be effected.

In operation of my apparatus, the operator N will bring the platform alongside the bed, as shown in Fig. 4, after the scoops have been placed beneath the patient and he has been fastened thereto by the straps 27. By properly manipulating the approach of the platform, the projecting handles 22 will be caused to slide into the receiving slots 50 at the tops of the plungers 44 and 45 and locked therein as described above. The patient may then immediately be elevated a desired distance above the bed by actuation of the pedal 62 and then pulled away from the bed and moved to any desired position as shown in Fig. 5, for example. When it is desired to return the patient to the bed, this operation is repeated in reverse, the plungers being lowered by operation of a release valve 65 in known manner.

The invention in its broader aspects is not limited to the specific mechanisms shown and described but departures may be made therefrom within the scope of the accompanying claims without departing from the principles of the invention and without sacrificing its chief advantages.

What I claim is:

1. Apparatus for handling recumbent persons including in combination a supporting member of area sufficient to underlie a substantial portion of a person's body, a handle connected to said member for introducing said member beneath a person's body, said handle extending rigidly from said member to a locus remote from said person's body when the member so underlies said body, and means attachable to the handle adjacent said locus for providing cantilever support to said handle, member and person lying thereupon.

2. Apparatus for handling recumbent persons

including in combination a supporting member of area sufficient to underlie a substantial portion of a person's body, a handle connected to said member for introducing said member beneath a person's body, said handle extending rigidly from said member to a locus remote from said person's body when the member so underlies said body, a carriage movable toward and away from said locus, and means on said carriage and attachable to the handle adjacent said locus for providing cantilever support to said handle, member and person lying thereupon.

3. Apparatus for handling recumbent persons including in combination a supporting member comprising a shallow concave plate of area sufficient to underlie a substantial portion of a person's body, a handle connected to said member for introducing said member beneath a person's body, said handle extending rigidly from said member to a locus remote from said person's body when the member so underlies said body, and means attachable to the handle adjacent said locus for providing cantilever support to said handle, member and person lying thereupon.

4. Apparatus for handling recumbent persons including in combination a pair of supporting members of area sufficient to underlie a substantial portion of a person's body, handles connected to either member for introducing said members individually beneath a person's body, said handles extending rigidly from said members to loci remote from said person's body when the respective members so underlie said body, and means attachable to the handles adjacent said loci for providing cantilever support to said handles, members and person lying thereupon.

5. Apparatus for handling recumbent persons including in combination a pair of supporting members of area sufficient to underlie a substantial portion of a person's body, handles connected to either member for introducing said members individually beneath a person's body, said handles extending rigidly from said members to loci remote from said person's body when the respective members so underlie said body, a carriage movable toward and away from said loci, said carriage having means for detachably engaging said handles adjacent said loci for providing cantilever support to the handles, members and person lying thereon.

6. Apparatus for handling recumbent persons including in combination a pair of supporting members of area sufficient to underlie a substantial portion of a person's body, handles connected to either member for introducing said members individually beneath a person's body, said handles extending rigidly from said members to loci remote from said person's body when the respective members so underlie said body, a carriage movable toward and away from said loci, said carriage having supporting means for detachably engaging said handles adjacent said loci for providing cantilever support to the handles, members and person lying thereon and operator-controlled elevating means on the carriage for raising and lowering the handles, members and person while so supported.

7. Apparatus for handling recumbent persons including in combination a pair of supporting members of area sufficient to underlie a substantial portion of a person's body, handles connected to either member for introducing said members individually beneath a person's body, said handles extending rigidly from said members to loci remote from said person's body when the respective members so underlie said body, a carriage movable toward and away from said loci, said carriage having supporting means for detachably engaging said handles adjacent said loci for providing cantilever support to the handles, members and person lying thereon and operator-controlled elevating means on the carriage for raising and lowering the handles, members and person while so supported.

8. Apparatus for handling recumbent persons

tive members so underlie said body, a carriage movable toward and away from said loci, said carriage having a pair of upstanding vertically movable hydraulic jack plungers spaced apart and having means for rigidly engaging the projecting handles to provide cantilever support therefor, and operator-controlled means for raising and lowering said plungers together to lift the person lying upon the supporting members from the bed and to lower him as desired.

8. Apparatus for handling recumbent persons including in combination a pair of supporting members of area sufficient to underlie a substantial portion of a person's body, handles connected to either member for introducing said members individually beneath a person's body,

said handles extending rigidly from said members to loci remote from said person's body when the respective members so underlie said body, a carriage movable toward and away from said loci, 5 said carriage having a pair of upstanding vertically movable hydraulic jack plungers spaced apart and having means for rigidly engaging the projecting handles to provide cantilever support therefor, operator-controlled means for raising 10 and lowering said plungers together to lift the person lying upon the supporting members from the bed and to lower him as desired, and means for varying the lateral distance between said plungers for engagement with said projecting handles.

JOHN E. LEINAHAN.
